Atty.

UNITED STATES PATENT OFFICE.

GEORGE THORP, OF PORTSMOUTH, MICHIGAN.

VICE.

SPECIFICATION forming part of Letters Patent No. 392,378, dated November 6, 1888.

Application filed March 8, 1888. Serial No. 266,589. (No model.)

To all whom it may concern:

Be it known that I, GEORGE THORP, a citizen of the United States, residing at Portsmouth, in the county of Bay and State of Michigan, have invented certain new and useful Improvements in Vises; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in vises, and more particularly to that class of vises in which the nut, or the device retaining the nut in rigid position, may be disengaged from its clutch or holding contact, and thereby permit the movable jaw of the vise to freely pass in either direction in order to adapt the opening between the jaws to pieces of various sizes more quickly than by the more common method of turning the screw to effect the change in the said opening; and the present invention pertains particularly to devices for retaining the nut in position or for releasing the same at the will of the operator.

The invention consists in the combination, construction, and arrangement of the several devices which are assembled together for the purpose of attaining the result set forth, and which are hereinafter more fully described, and specifically pointed out in the claims; and the objects of my invention are to provide devices whereby the jaws of a vise may be more easily and quickly opened or closed than by the devices in common use for that purpose, and whereby the manipulation of the screw-lever only attains the desired result, so that one hand only need be used to perform the operation of quickly expanding or contracting the space between the jaws of the vise.

Another object of the said invention is to provide a vise with a means of disengaging the nut from its holding contact, which shall be cheaply and easily constructed and effective in its operation, and which will provide the said nut with a sustaining-support upon each side of the screw, so that the nut will be submitted to an even and true pulling strain by the screw, whereby the cramping or twisting strain which obtains when the nut is sup-

ported upon one side only is avoided and the working parts of the device rendered more durable and lasting.

I attain the aforesaid objects by means of the devices illustrated in the accompanying drawings, in which—

Figure 1 is a vertical central section of a vise containing my improvements. Fig. 2 is 60 a horizontal section of the same, taken at *xx* in Fig. 1, and shows the holding devices for the nut in a disengaged position. Fig. 3 is the same with the retaining devices in engagement and holding the nut rigidly in position. 65 Fig. 4 is a plan view of the inner end of the movable arm and of the pieces retaining the nut in position. Fig. 5 is a vertical longitudinal section of the rigid jaw and arm and shows the ratchet inside of the arm. Fig. 6 70 is a side view of one of the pieces retaining the nut in position.

The same letters designate similar parts throughout the several views in the drawings.

a represents the rigid or stationary jaw of a 75 vise, and is provided with an arm, *b*, through which is arranged a longitudinal opening, *c*, and which is secured in any convenient manner to the bench *d*. The inner vertical sides of the said opening *c* are provided with ratchet-teeth, as *e*, and within the opening *c* is placed a hollow arm, *f*, having upon its outer end a jaw, *g*, which extends upwardly to meet and oppose the jaw *a*.

h is a shaft passed longitudinally through 85 the opening in the hollow arm *f*, and is provided upon its outer end with a collar, *i*, and a screw-lever, *j*, and is also provided for a short distance upon its inner end with a screw-thread, as *k*, and a collar, *l*, is passed upon the 90 shaft *h* and firmly secured in position inside of and against the portion *m*, which partially closes the outer end of the hollow arm *f*, leaving a central opening, however, for the shaft, and operates, together with the collar *l*, to prevent the shaft from withdrawing from the arm and to support the shaft centrally within the hollow arm.

n is a nut provided with a central opening and passed upon the threaded end *k* of the 100 shaft *h*, and is arranged so that its front end forms the square shoulders *o*, and upon the lateral sides of the said nut are placed the retaining-pieces *p*. These pieces *p* are pivotally se-

cured near their front ends, at *q*, to the sides of the nut *n*, and are provided on their front ends with the portions *r*, projecting inwardly and forming shoulders, against which rest the 5 shoulders *s* of the nut, and are also provided upon the rear portions of their outer sides with the ratchet-teeth *s*, so arranged as to engage with the teeth *e*, or to close toward the said nut and pass the said teeth *e* without engaging 10 therewith, as desired. The rear ends of the pieces *p* are provided with the portions *t*, projecting inwardly toward each other, and upon the front edges of these projections are arranged the inclines *u*. The lateral sides of the rear 15 ends of the hollow arm *f* are removed, and the upper side, *a'*, thereof is left to extend rearward over the nut, as is also the lower bottom portion, *b'*, thereof, beneath the nut. A portion of the lateral sides of the rear ends of 20 these portions *a'* and *b'* are removed, forming the inclined sides *e'*, facing outwardly and rearwardly and adapted to engage with the inclined portions *u* of the pieces *p* and crowd the pieces *p* outwardly when the screw-shaft *h* is revolved 25 for closing the jaws *a* and *g* toward each other.

e' is a collar placed upon the rear end of the screw-shaft and in such a position that when the nut is moved rearward and closed against the collar *e'* the teeth *s* on the retaining-pieces 30 *p* will be entirely disengaged from contact with the ratchet-teeth *e*, which leaves the arm *f* free to be moved in either direction, as desired.

d' is a spring placed within the hollow arm 35 *f*, and is arranged to bear outwardly against the front ends of the pieces *p* and hold the rear ends of the pieces *p* against the lateral sides of the portions *a'* and *b'*, and, when the proper position is reached, to close the said pieces 40 over the inclines *e'*.

The operation of the device is as follows: The parts being placed in position, as shown 45 in Figs. 1 and 2, with the inclines *u* against the inclines *e'*, the ratchet-teeth *s* are free from engagement with the teeth *e* and the arm *f*, and jaw *g* is free to be moved outwardly or inwardly, as desired, and, the desired position of the jaw *g* being reached, the shaft *h* is revolved for closing the jaws together, which 50 action moves the nut *n* toward the front and forces the pieces *p* outwardly by the action of the inclines *u* and *e'* until the ratchet-teeth *e* engage with each other, and then the arm *f* and jaw *g* move toward the rear, and when the 55 said inclines *u* and *e'* pass each other the ratchet-teeth *s* and *e* are in full engagement and are retained in that position by the lateral or parallel sides *d'* and *e'* of the portions *a'* and *b'*, which engage with the inner edges of 60 the projecting portions *t* and allow the arm *f* to move inward to some distance, and the operation of the parts, when in this position, is the same as the operation of an ordinary vise, the nut being retained rigidly in position so 65 long as the portions *t* engage with the said parallel sides.

In order to release the retaining-pieces *p*

from engagement with the ratchets *e*, the screw-shaft *h* is revolved for moving the arm *f* outwardly until the inclines *u* and *e'* pass over 70 each other, and the spring *d'* then operates to close the retaining-pieces *p* toward each other until the teeth *s* are freed from engagement with the teeth *e*, which bring the collar *e'* in contact with the rear end of the nut and stops 75 the rotation of the screw-shaft, and the arm is then free to be moved in either direction.

By means of the arrangement of the parts as described an exceedingly durable and convenient device is produced, as the construction of the retaining-pieces and the ratchets is such as to obtain the most rigid and firm support for the nut upon all its sides, which avoids any cramping or twisting of the nut upon the screw-which obtains by drawing 85 from one side only, and allows the movable jaw to be quickly and easily changed to permit pieces of greatly-differing sizes to be placed between the jaws, and avoids the slow process in common use of changing the space 90 between the jaws by turning the screw.

Another and prominent feature of this device is its cost of manufacture, which is slightly in excess of an ordinary vise, the working parts being few and not at all liable to get out of order, and their strength and durability are by 95 their peculiar construction and arrangement rendered as great as, if they do not exceed, that of an ordinary vise; and it is very evident that by the use of the detachable retaining 100 devices for the nut, as herein set forth, a very great saving of time is obtained, and the trouble and annoyance of manipulating the screw for moving the jaw outwardly or inwardly to a great distance are avoided.

Having described my invention, what I claim as new, and desire to secure by Letters Patent is—

1. In a vise, the combination, with the stationary jaw provided with a longitudinal opening, the ratchets *e* upon the lateral sides of the said opening, the hollow arm *h*, passed into the said longitudinal opening and provided on its rear end with the extended upper portion, *a'*, and lower portion, *b'*, having the inclines *u*, the screw-shaft passed through the arm *h* and provided with a screw-thread, *k*, and the nut *n* upon the screw, of the retaining-pieces *p*, pivotally secured to the lateral sides of the said nut and provided with the ratchet-teeth *s*, engaging with the said ratchets *e*, and having the inwardly-projecting portions *t*, provided with the inclines *e'*, engaging with the said inclines *u*, and the collar *e'*, upon the rear end of the shaft, substantially as and for the 125 purpose set forth.

2. In a vise, the combination, with a jaw, *a*, having the arm *b*, provided with a longitudinal opening, *c*, the ratchets *e* upon the lateral sides of the said opening, the movable jaw *g*, 130 provided with the hollow arm *f*, having on its rear end the inclines *u*, the shaft *h*, passed into the arm *f* and provided with a screw-threaded end, *k*, and the nut *n* upon the end *k* and provided

with the shoulders *o*, of the retaining-pieces *p*, pivoted to the lateral sides of the said nut and provided upon their outer sides with the teeth *s*, and having on their front ends the inwardly-projecting portions *r*, engaging with the said shoulders *o*, and on the rear ends the inwardly-projecting portions *t*, provided with the inclines *c*, and the spring *d*, for moving the

rear ends of the said pieces *p* toward each other, substantially as and for the purpose set forth. 10

In testimony whereof I affix my signature in presence of two witnesses.

GEORGE THORP.
